(57) **CLAIM**

The ornamental design for a grip for ice fishing reel, as shown and described.

DESCRIPTION

FIG. 1 is a perspective view of a grip for ice fishing reel according to my new design;

FIG. 2 is a top view thereof;

FIG. 3 is a front view thereof, wherein the rear view is the same;

FIG. 4 is a bottom view thereof; and,

FIG. 5 is a right side view thereof, wherein the left side view is the same.
